George L. Clare

INVENTOR

BY Victor J. Evans

ATTORNEY

John H. L. Clark
WITNESS:

UNITED STATES PATENT OFFICE

GEORGE L. CLARE, OF CHICAGO, ILLINOIS

TELEPHONE-MOUTHPIECE STERILIZER

Application filed April 17, 1929. Serial No. 355,792.

This invention relates to certain new and useful improvements in means to facilitate the application of antiseptics upon the transmitters of public telephones to prevent the spreading of diseases.

Another object of the invention contemplates the provision and arrangement of a squeegee for this purpose.

An additional object of the invention embodies a mounting for the squeegee whereby the latter may be shifted to wipe and cleanse the mouth piece or transmitter.

With the above and other objects in view, the invention further consists of the following novel features and details of construction, to be hereinafter more fully described, illustrated in the accompanying drawing and pointed out in the appended claims.

In the drawing:—

20 Figure 1 is a longitudinal sectional view taken through the invention as applied for use.

Figure 2 is a rear elevation of a telephone transmitter showing the position of the invention in dotted lines.

Figure 3 is a perspective view of the squeegee.

Figure 4 is a perspective view of a mounting for the squeegee upon the transmitter.

30 Referring to the drawing in detail wherein like characters of reference denote corresponding parts, the reference character 10 indicates the conventional form of transmitter employed upon public telephones having an exteriorly threaded attaching sleeve projecting from the innermost end thereof and a foraminated disk like partition 12 subdividing the body portion and attaching sleeve of the transmitter.

40 The invention comprises a base or mounting in the nature of a disk 13 having prongs or extensions 14 radially and rightangularly disposed tangentially thereof for projection within the adjacent foraminations in the partition wall 12 of the transmitter as near to the center of the latter as possible, as substantiated from the illustrations of my invention in Figures 1 and 2 of the drawing.

Said disk is provided with a central aperture 15 to accommodate a rivet or other head-

ed stud, such as indicated at 16, the purpose of which will be presently apparent. The prongs or extensions 14 are subsequently inwardly offset upon themselves against the rear wall of the partition or foraminated disk 12 to retain the stud and disk 13 against displacement.

An arm 17 of elongated shape is bent in conformity with the inner side wall of the transmitter whereby the squeegee or other absorbent material, such as indicated at 18, carried upon the outer surface thereof will evenly and effectively engage the transmitter. Staples or yokes, such as indicated at 19, are employed as the means of fastening of the squeegee upon the arm. A hook or open looped portion 20, formed upon the outermost end of the arm 17, is bent around and about the outermost flared periphery of the transmitter to provide a guard and guide for the arm and squeegee while in use.

The opposite and innermost end of the arm 17 includes an inwardly offset portion 21 having communication with an extension 22; the latter carrying a centrally apertured enlargement or extremity 23. The stud 16 is passed through the aperture in the enlargement or extremity 23 to provide a mounting for the innermost end of the arm and a bearing therefor whereby the sterilizer may be whipped around in concentric circles to coat the inner surface of the transmitter with a film or coating of antiseptic to destroy any germs which may have accumulated. The antiseptic retained by and discharged from the squeegee may be replenished by pouring a few drops upon the inner surface of the telephone transmitter or mouth piece and shifting the squeegee around to this position to absorb same.

Although I have shown and described my invention as being primarily designed for application upon and in conjunction with the mouthpieces or transmitters of telephones, it is to be understood that the invention may be equally and effectually as well applied upon the transmitters of speaking tubes in the hallways of apartment houses and the mouthpieces of sound recording and reproducing machines.

The invention is susceptible of various

changes in its form, proportions and minor details of construction, and the right is herein reserved to make such changes as properly fall within the scope of the appended claims.

Having thus described the invention,
5 what is claimed is:

1. A sterilizer mouthpiece comprising a disk arranged centrally thereof, an arm pivotally mounted for circumferential movement from said disk and within the mouthpiece, a hook formed upon the arm engageable with the periphery of the mouthpiece to guide said arm concentrically thereof, and a squeegee saturated with a suitable antiseptic being arranged upon the outer side of said arm to wipe against and coat the adjacent surface of the mouthpiece to remove and prevent the accumulation of infectious disease germs.

2. A sterilizer mouthpiece comprising a disk arranged centrally thereof, an arm pivotally mounted for circumferential movement upon said disk and within the mouthpiece, a squeegee saturated with a suitable antiseptic being arranged upon the outer side of said arm to wipe against and coat the adjacent surface of the mouthpiece to remove and prevent the accumulation of infectious disease germs, and a hook carried upon the outermost projecting end of the arm and extended about the adjacent periphery of the mouthpiece being sprung terminally thereof against the outer surface of the mouthpiece to insure frictional contacting engagement of the squeegee with the inner surface of the mouthpiece.

35 In testimony whereof I affix my signature.
GEORGE L. CLARE.
